UNITED STATES PATENT OFFICE.

JOHN H. DALE, OF NEW YORK, N. Y., ASSIGNOR TO DALE LIGHTING FIXTURE CO., INC.,
A CORPORATION OF NEW YORK.

ELECTRIC INCANDESCENT LAMP.

1,231,335.

Specification of Letters Patent. Patented June 26, 1917.

Application filed March 5, 1915. Serial No. 12,298.

To all whom it may concern:

Be it known that I, JOHN H. DALE, a citizen of the United States, residing at the city of New York, in the borough of Manhattan and State of New York, have invented certain new and useful Improvements in Electric Incandescent Lamps, of which the following is a full, clear, and exact description.

- 10 This invention relates to electric incandescent lamps and especially to a type of lamp which has been recently developed, and is known as the "nitrogen" lamp, which is of intense brilliancy and high candle power.
- 15 The heat generated by such lamps is also very great, possibly due to the circulation of the nitrogen gas within the sealed bulb, the heat from the filament being carried to the lamp bulb by the gas and transmitted
- 20 by conduction to the lamp base in sufficient quantities to heat the latter to a temperature considerably higher than that which is considered safe for installation. Frequently the temperature to which the base
- 25 is heated is sufficiently high to take the temperature from the spring contacts and other parts of the base and its connecting socket, as well as giving rise to other serious objections to the commercial use of lamps of this character.
- 30 It is the purpose of this invention to prevent or lessen the transmission of the heat from the glass bulb to the lamp base and to thereby lower the temperature of the base.
- 35 To accomplish this, the invention contemplates a construction by which the lamp base is separated from the neck of the bulb by a space or chamber, and yet the base is supported upon the lamp bulb in such a
- 40 manner that the heat of the bulb cannot be transmitted directly by conduction to any material extent to the lamp base. This space is preferably used to ventilate the lamp base.
- 45 The invention also consists of the constructions and combinations which will be hereinafter set forth in detail and particularly pointed out in the appended claims.

In the accompanying drawings:

- 50 Figure 1 is a view partly in section and

partly in elevation of my preferred embodiment of a lamp;

Fig. 2 is a transverse section taken on the line 2—2 of Fig. 1, looking in the direction of the arrows;

55

Fig. 3 is a detail of a modified form of structure; and

Fig. 4 is a detail of another modification.

One form of lamp bulb with which the invention is adapted to be used is of the usual shape and size which has been adopted for "nitrogen" lamps and comprises a substantially spherical-shaped body portion 1 and an elongated cylindrical neck 2. Extending downwardly through the elongated neck 60 2 is a hollow post or stem 3 which is joined to the neck at its upper end so as to form the sealed bulb. The stem 3 carries at its lower end a pedestal 4 from which the filament 5 is supported by means of radiating 65 arms 6. Current is supplied to the filament by means of conductors 8 and 9, respectively, which are of sufficient cross section and rigidity to aid in sustaining the filament in position. These conductors pass through 70 the closed lower end of the hollow post 3 and the interior of the same to the upper end of the neck 2 of the lamp, and are adapted to be connected to the lamp base, as will be later referred to.

80

In the form of lamps shown in Figs. 1 and 3, the lamp base proper, which will be later described, is supported upon the lamp by means of a skirt 10 which is similar to the one used in the existing forms of nitrogen lamp, and which is secured to the upper end of the neck by an annular ring of cement 11, in the usual manner. This ring of cement, while being unaffected by the heat in the sense that it will not disintegrate 90 or lose its adhesiveness under the action of heat, is not a heat insulator, and the heat of the bulb is transmitted to it so that it reaches approximately the same temperature as the neck of the lamp. This is due also to the 95 fact that the lower end of the skirt 10 is in direct contact with the neck of the bulb.

The lamp base proper comprises a skirt 12, which has secured to it by means of the glass insulation 13, the usual screw plug 14. 100

The skirt 12 is, however, of considerably larger diameter than the skirt 10, so that these two parts, when assembled, are separated by a space or chamber 15. The skirt 12 is secured to the skirt 10 in the form as shown in Fig. 1, by means of a ring or washer 16 of heat insulating material. The lower edges 17 and 18 of the skirts 10 and 12, respectively, are bent around the bottom surface of this ring forming annular flanges while the portion of both the skirts adjacent the top face of the ring are swaged inwardly so as to provide a groove in which the ring of heat insulating material seats. 5 The adjacent edges of the flanges 17 and 18 are not in contact so that the direct transmission of heat by conduction is prevented. Suitable ventilating openings 19 are provided in the ring 16. Other ventilating openings 20 are provided in the skirt 12 adjacent its connection to the screw plug, the openings in the ring and skirt being spaced but a slight distance apart so that a circular row of holes is provided in each instance. The 25 construction described is sufficient to rigidly support the lamp base upon the skirt 10. The center contact 21 of the screw plug is secured to the conductor 8, while the conductor 9 is soldered or otherwise electrically 30 connected to the lower edge of the screw plug 14 in the usual manner. In assembling these parts the lamp base and ring 16 are secured to the skirt 10 and the latter is thereafter secured to the lamp bulb, in the usual 35 manner, and when the lamp is lighted the circulation of the nitrogen gas within the lamp bulb, which causes the neck of the bulb to become highly heated, will cause the skirt 10 to be heated to approximately the same 40 temperature. The radiation of heat from this surface causes the air within the annular chamber 15 to become heated, the heated air rising in the chamber and passing out through the openings 20 will leave a space 45 for the cooler air surrounding the lamp to pass into the annular chamber through the openings 19, the circulation once established being maintained until the lamp is again extinguished, and the parts become cool. The 50 circulation of air in this manner, therefore, lowers the temperature of the skirt 12 of the lamp base as well as the screw plug 14. The transmission of heat by conduction is prevented by the interposition of the heat 55 insulating ring between the two skirts.

In the form shown in Fig. 3 the heat insulating ring 16 is omitted and the skirt 10 is bent over to provide an annular flange 22 which is joined at its outer edge to the lower 60 edge of the skirt 12 by means of a bead 23 formed by curling the edges of the skirts over each other. The other features of construction of the base are similar to that described, and the construction is equally efficient with the exception that some heat may 65

be transmitted by conduction across the metallic flange 23, but since there is a plurality of circular holes arranged within this flange, the conducting surface is reduced to a minimum and a sufficient quantity of heat cannot 70 be conducted in this manner to cause a heating of the skirt 12 to a high temperature.

While I deem the form of lamp base with the ventilated passages as shown in Figs. 1 and 3 of the drawing to be the preferred embodiment of my invention, yet the construction which is shown in Fig. 4 may be used. In this construction, as before, the metallic skirt 10 is cemented to the neck of the lamp 75 bulb by a layer of cement 11.

The lamp base in this form comprises the usual screw plug 14 which is mounted and secured in place upon a skirt by means of glass insulation 13 as previously described. The skirt, however, in this form is cut away 85 so as to provide an annular hub 27 upon which the screw plug rests, and a plurality of ribs 26 which are preferably three in number, although a greater or less number may be used. These ribs are connected to 90 the metallic skirt which is rigidly secured to the neck of the bulb by connecting pieces 26'. The plug 14 of the base, while rigidly supported by the lamp bulb, is nevertheless out of direct contact with the neck of the 95 bulb and is spaced a considerable distance therefrom so that it will remain practically unaffected by the heat radiating from the lamp bulb which heat dissipates into the surrounding air. Moreover, sufficient heat can- 100 not be transmitted by conduction over the metallic pieces 26' and ribs 26 to heat the screw plug to any material extent.

While I have shown several modifications of the invention, yet it is apparent that still 105 further modifications and ramifications may be produced and it is not my intention to be limited to the specific embodiment shown, since I deem a construction in which the lamp base, while being separated from the 110 lamp bulb to provide a heat insulating zone between the two, is rigidly supported thereby, to be novel with me, and hence I desire to be limited only by the scope of the appended claims.

I claim:

1. An electric incandescent lamp comprising a lamp bulb having a neck, a metallic part rigidly secured on the end of said neck, a lamp base comprising a screw plug and a 120 skirt, and means connecting said metallic part to said skirt and supporting the latter with a ventilating space between said skirt and the metallic part.

2. An electric incandescent lamp comprising a lamp bulb having a neck, a ring rigidly secured to said neck, a lamp base consisting of a screw plug and a skirt, an annular ring connecting said skirt and ring and supporting them with a space between the two, said 130

annular ring and skirt having ventilating openings therein.

3. An electric incandescent lamp comprising a lamp bulb having a neck, a ring rigidly secured to said neck, a lamp base consisting of a screw plug and a skirt, an annular ring of heat insulating material connecting said skirt and ring and supporting them with a space between the two, said annular ring

and skirt having ventilating openings 10 therein.

In witness whereof, I subscribe my signature, in the presence of two witnesses.

JOHN H. DALE.
